MAGNETRON

Howard L. Steele, Jr., Bloomfield, N. J., assignor
to Westinghouse Electric Corporation, East
Pittsburgh, Pa., a corporation of Pennsylvania

Application June 18, 1946, Serial No. 677,464

6 Claims. (Cl. 250—27.5)

1

This invention relates to magnetrons, and more particularly to introduction and utilization of electrons within a hollow anode.

The usual magnetron provides an anode surrounding a cathode coaxial therewith, the anode having cavity resonators radiating therefrom and the cavities constituting said resonators, as well as the central hollow or cavity for the cathode all opening into end spaces at each end of the anode. For reasons not believed necessary to discuss here, many electrons emitted by the cathode return thereto after excursion in and absorption of energy from the region between the cathode and anode. The excess energy of the returning electrons is converted into heat in the cathode, and tends to overheat and destroy the cathode.

An object of the present invention is to provide a magnetron the cathode of which is removed from the region where affected by electron bombardment.

Another object of the invention is to provide a cathode which is outside the anode region but which will introduce electrons to that region.

A further object of the invention is to obtain electron functioning within the anode as if produced therein upon electrons produced externally of the anode.

Yet another object of the invention is to maintain the usual anode and cavity dimensions and arrangement inclusive of a core corresponding to dimensions and position of the cathode of the prior art.

Still further objects include the provision of electron beaming structure within an end space; to prevent any substantial return flow of electrons; to provide for copious electron emission and control thereof; and to obtain simplicity of construction and increased efficiency of operation.

Other objects of the invention will appear to those skilled in the art to which it appertains as the description proceeds, both by direct recitation thereof and by implication from the context.

Referring to the accompanying drawing in which like numerals of reference indicate similar parts throughout the several views;

Figure 1 is a vertical diametric section of a magnetron embodying my invention;

Figure 2 is a horizontal section beneath the top closure, as on line II—II of Figure 1;

Figure 3 is a fragmentary section of the cathode as shown in Figure 1 but on enlarged scale;

Figure 4 is a plan of the grid; and

2

Figure 5 is a vertical diametric sectional view, on the plane including the lead-in wire, of the focusing collar.

The present magnetron, as in the prior art, provides a magnetron body 10 of generally cylindrical configuration and provided therein with end spaces 11, 12 sealed vacuum tight by end or cover plates 13. One of these end spaces, as 11, is deeper than the other to accommodate mechanisms described hereinafter and since in the drawing the deeper end space is the one nearest the top of Figure 1, it will be arbitrarily referred to for brevity as the upper end space without being restrictive as to position in use.

Within the magnetron the body provides an anode 14 of generally cylindrical shape and shorter than the outside of the body so as to provide the said end spaces 11, 12 at opposite ends of the anode. Within the anode and in direct communication with and between the end spaces, is an axial cavity 15 from which radiate suitable cavities 16, functioning as cavity resonators, which are open-ended into the said end spaces 11, 12. Between the radiating resonator cavities 16 the anode is accordingly formed with radiating segments 17 thereby forming what may be termed a multi-segment anode. Following usual practice, alternate segments are preferably electrically connected at their ends and next the axial cavity by split rings, known in the art as straps 17'.

In the prior art it is usual to provide a cathode coaxially within the axial cavity 15, but in the present invention I provide thereat a core 18, which may be referred to as a dummy cathode in that it is the size and shape of the usual cathode and occupies the position normally occupied by a cathode, but is not intended primarily for emissive purpose. The desired characteristic of this core 18 is its ability to resist erosion or deterioration by heat and by its location to maintain usual electro-magnetic modes of the energy propagation within the axial cavity. These desideratum may be accomplished by utilization of a ceramic material for said core, but inasmuch as I desire to apply a potential to said core, it is preferably made of an appropriate metal, of which tungsten, molybdenum and the like are examples. While these metals, and in fact, all metals, are more or less emissive of electrons, the one selected is preferably a poor emitter but capable of withstanding high temperatures. The lower end of said core may conveniently carry a hat 18' of approximately the diameter of the cathode cavity.

According to the present invention, a cathode 19, of ring configuration the plane of which is normal or perpendicular to the axis of the cavity, is provided in upper end space 11 and constructed and arranged to beam its electrons downwardly into the axial cavity 15. The structure therefore provides a cathode which is entirely outside of the axial cavity of the anode, remote from that cavity, but profusely emissive of electrons which enter the said cavity and function with respect to the anode and its cavity resonators comparable to electrons of the prior art emitted from a coaxial cathode directly in said axial cavity. For mechanically supporting and electrically isolating said core, the upper end thereof is shown attached to a lead-in wire 20 which extends upwardly and then radially therefrom in end space 11 through the side of the magnetron body, free of contact therefrom and rigidly carried by a usual lead-in insulating and sealing structure 21.

Aforementioned cathode 19 may be variously fabricated, the selected construction herein comprising a flat ring 22 as shown in Figure 3, the under face of which is electron emissive as by an oxide coating such as barium oxide, strontium oxide, or other coating 23 thereon. Adjacent to, and here shown above, the ring 22 is a heater wire 24 one end of which connects, as at 25, to a humped shell 26 of incomplete circular shape fixed on the upper face of said ring 22. Said shell is welded or otherwise made integral at its peripheral rims to the peripheral rims of said ring, thereby constituting an enclosure for insulative material 27 therein and within which the heater wire 24 is embedded. The end of the cathode thus formed and to which the heater wire is attached is carried by a lead-in wire 28 which projects radially therefrom through the end space 11 and through the side of the magnetron body free of contact therefrom and carried rigidly by a usual lead-in insulating and sealing structure 29. The other end of the heater wire 24 is made fast, as by spot welding, to a bracket 30 which in turn is secured upon another lead-in wire 31 which likewise projects radially through the end space 11 and through the side of the magnetron body free of contact therefrom and carried rigidly by a usual lead-in insulating and sealing structure 32.

Below the cathode and interposed between said cathode and end of the anode, is a focusing collar 33 the purpose of which is to direct electrons as a beam from the cathode into the axial cavity of the anode. The construction shown, therefore, provides that the anode and its axial cavity, said collar 33 and cathode 19 as well as core or dummy cathode 18 are all coaxial and that the inside diameter of said collar is slightly less than the diameter of the axial cavity 15 of the anode. Said focusing collar is out of contact from the cathode and anode, and is shown rigidly supported by a lead-in wire 34 projecting radially therefrom through the end space 11 and through the magnetron body free of contact therefrom and carried by a usual lead-in insulating and sealing structure 35.

If so desired, a flat, washer-like grid 36 may be interposed between the cathode and focusing ring, coaxial therewith. Such a grid is here shown, and for electrically connecting and rigidly mounting the same is secured at one part of its periphery to a lead-in wire 37 which projects radially through the side of the magnetron body free of contact therefrom and carried by a usual lead-in insulating and sealing structure 38.

It may be here stated that all of the above described lead-in structures 21, 29, 32, 35 and 38, may be alike, and consequently the sectional showing in Fig. 1 of structure 32 is exemplary of all others as well. Each includes a radio frequency choke 39 and a glass seal 40.

An energy pick-up or output loop 41 is provided in one of the cavity resonators, preferably one most remote from the aforementioned lead-in wires, said loop making connection with the usual coaxial line output structure 42 which includes, as will be understood, an appropriate seal so the evacuated condition of the interior of the magnetron body shall not be lost.

By virtue of the several electrodes (in which term is included core or dummy cathode 18) each having a lead-in wire thereto, the device may be variously connected and used. As one example of use, the focusing collar 33 is connected to have a potential near to that of the high negative potential of the cathode, the anode of course being at ground or positive potential, in this case grid 36 would probably have to contribute to a positive field in order to get sufficient emission into the axial cavity as the penetration of the relatively positive field from the anode will be reduced due to presence of the potential on the focusing collar. Varying the potential of the collar under these conditions gives it a grid action of its own by virtue of its effect on the penetration of the field from the anode. The usual magnetic field employed with magnetrons obtains spiralling of the electrons in the said axial cavity and the electrons accordingly function in said axial cavity substantially as if emitted from the core or dummy cathode. The focusing collar at its high-negative potential prevents substantial return travel of the electrons back to the cathode. The advantage is thus gained that the cathode is not subjected to excessive heating by back-bombardment, which is especially important for direct current and continuous wave operation. The cathode, in the absence of secondary emission from the core, must be large enough to supply all the emission, but with direct current, the power that can be dissipated by the anode will be a limitation of the current at which the magnetron should operate. However, some secondary emission from the core 18 is permissible to augment the primary emission from the cathode, and with the core of a high melting point material, cooling thereof need not be included. With continuous wave operation the core attains a much higher temperature than with pulsed operation and in that event inclusion of good heat conduction therefrom or even forced cooling may be provided. The copious emission from the cathode makes it unnecessary for the core to be a good secondary emitter, and by preference, especially when used for amplitude modulation, the core is preferably a poor secondary emitter.

As a further example of use of the device, the focusing collar 33 may be held at or near ground potential, operating below cutoff so far as the ordinary anode-cathode region is concerned. This lends itself to amplitude modulation, as the emitting cathode is in position where its emission can be controlled by grid 36. Again the collar 33 can itself have a grid like effect as a changing positive potential would influence emission but would collect only those electrons emitted from the outer edges of cathode by virtue of the fact that the magnetic field cuts off the emission from near the center. In the ordinary magnetron with coaxial cylindrical cathode, grid control is

not feasible, or at least difficult at best, because the crossed magnetic field soon spirals the electrons and any configuration of grid structure for any practical purposes will find electrons approaching it from all directions. In the present showing, however, the location of the grid closely in advance of a cathode perpendicular to the magnetic flux obtains a control of electrons before spiralling alters the common general direction of the electrons, and grid control therefore is effective and feasible. In this grid controlled use of the device with amplitude modulation, it is preferable to operate at a spot on the performance diagram at which the frequency deviation will be minimum and where the radio frequency or power output lines are cut substantially at right angles to produce the change in amplitude with change of grid voltage.

Finally it may be said that by using a grid of washer shape, with the outside diameter thereof and of the cathode as large as or larger than the axial cavity of the anode, and the focusing collar at least as large thereas, the emission may be partly collimated by the magnetic field through the grid into the cavity resonator openings at the axial cavity, or what amounts to the same thing, into the cylindrical straps on the anode. This would give a grid tuning control whereas the emission through the washer-like hole of the grid would be maintained constant.

I claim:

1. A magnetron comprising an evacuated body providing an anode therein, said anode having an axial cavity and cavity resonators radiating therefrom, a cathode opposite an end of said axial cavity, and a substantially non-emissive core axially within the evacuated body and within and extending the full length of said axial cavity, said core being constructed of material completely resistive to deterioration from any heat developed in operation of the magnetron.

2. A magnetron comprising an evacuated body providing an anode therein, said anode having an axial cavity and cavity resonators radiating therefrom, a cathode opposite an end of said axial cavity, and a substantially non-emissive ceramic core axially in said axial cavity.

3. A magnetron comprising an evacuated body providing an anode therein, said anode having an axial cavity and cavity resonators radiating therefrom, a cathode opposite an end of said axial cavity, a substantially non-emissive conductive core selected from the group of metals of molybdenum, tungsten and the like axially in said axial cavity, and means at one end of said core both supporting the same and providing an external electrical connection therefor.

4. A magnetron comprising an evacuated body

providing an anode therein, said anode having an axial cavity and cavity resonators radiating therefrom, a cathode opposite an end of said axial cavity and having an emitting surface in a plane transverse to the axis of said cavity, a focusing collar interposed between said cathode and anode on a common axis therewith, and a core coaxial with both said axial cavity and said focusing collar and coextensive with the combined lengths thereof.

5. A magnetron comprising an evacuated body providing an anode therein, said anode having an axial cavity and cavity resonators radiating therefrom, a cathode opposite an end of said axial cavity and having an emitting surface directed toward said cavity, a focusing collar interposed between said cathode and anode on a common axis therewith, a conductive core coaxial with both said axial cavity and said focusing collar and coextensive with the combined lengths thereof, and separate lead-in connections for each of said cathode, focusing collar and conductive core, each of said lead-in connections being insulated from the anode.

6. A magnetron comprising an evacuated body providing an anode therein, said anode having an axial cavity and cavity resonators radiating therefrom, a cathode opposite an end of said axial cavity and having an emitting surface directed toward said cavity, a focusing collar interposed between said cathode and anode on a common axis therewith, a planar grid interposed between said cathode and focusing collar, and a core extending substantially from the plane of said grid coaxial with both said axial cavity and said focusing collar and coextensive with the combined lengths thereof.
